CONVERTING HYDROCARBONS

Arthur V. Danner, Villanova, Pa., assignor to
Socony-Vacuum Oil Company, Incorporated,
New York, N. Y., a corporation of New York

Application March 28, 1945, Serial No. 585,349

8 Claims. (Cl. 196—52)

1

This invention has to do with processes for the conversion of high boiling hydrocarbons of the nature of gas oil into motor fuel of high anti-knock capability, and is particularly concerned with processes of that nature which are carried out in the presence of solid adsorbent material.

While the process here set forth is useful for the production of motor fuels for use in any type of internal combustion engine, it is particularly suitable for the production of fuels for use in high compression ratio motors.

This process is particularly concerned with the joint operation of processes for the production of gasoline together with a relatively high production of olefinic gases and the conversion of such olefinic gases to useful motor fuel components of high anti-knock capability, and has for its principal object the operation of such processes in cooperation, one with another, whereby a greatly enhanced capability in gasoline manufacture is obtained.

It has as another object the provision of a unitary process whereby in a two step manner a gasoline is produced, and gaseous products of such reaction are recombined as liquid products of high anti-knock capability as compounds of said gasoline.

As another object it has the effecting of considerable economies in overall operation by the concurrent practise and proper coordination of certain heretofore independent process steps in a manner hereinafter disclosed.

In the cracking of hydrocarbons, certain processes frequently give rise when practised at their optimum conditions for yield of gasoline and anti-knock character of gasoline, to olefine products, normally gaseous or present mainly in the lower boiling portion of the gasoline produced. Among such processes are those wherein a solid catalyst of clay-like nature is suspended as a slurry in a liquid phase or mixed phase or vapor phase operation, similar in nature to ordinary thermal processing but conducted at a temperature sufficiently elevated to take advantage of the suspended, solid adsorbent. A process of this general type is described in Jenkins Patent No. 2,167,211. The gasoline produced directly from such processes, when freed of olefinic constituents, is of high anti-knock capability, but with the olefines present, is of lower value, of lower susceptibility to anti-knock additives, and has a lesser storage stability. Additionally, if sulfur be present in the gas oil originally cracked, significant amounts of lighter mercaptans and other low boiling sulfur compounds are present in the

2

gasoline so produced, and treatment for the removal of such compounds is necessary. Formerly, in sweetening, these compounds were changed to supposedly innocuous compounds, as disulphides remaining in the oil, but present practise demands the removal of such compounds, since the supposedly innocuous disulphides and other sulfur have been found to have a negative effect upon the lead susceptibility of the fuel in which they are present.

This invention is based upon the discovery that unusual and unexpected results, both in terms of operability, of quality and amount of products, and in terms of economic operation, can be obtained by a proper setup of operative processes, as set forth hereinafter.

In order that my process may be understood readily, reference is now made to the drawing attached to and made a part of this specification, 15 the single figure of which shows one operating setup for the practise of my invention.

In the drawing a cracking stock which may be a gas oil of normal characteristics, with or without admixed heavy naphtha, is introduced 20 through pump 1 and pipe 2 to pass through heating coils 3, 4 and 5 in furnace 6 and is then discharged through pipe 7 under the control, if desired, of a back pressure valve 8 into vapor separator 9. A solid particle form adsorbent material, as and for a purpose hereinafter described, 25 having been added to the charged by pipe 10, the tar separated in vapor separator 9 and leaving through pipe 11 will contain substantially all of that contact mass material. In many cases to prevent entire vaporization of the furnace effluent in vapor separator 9, it is necessary to introduce a quenching oil, later to be described, through pipe 12. Vapors from vapor separator 9 pass through vapor line 13 to fractionator 14, 30 there to be separated into a heavier than gasoline portion leaving the fractionator 14 through pipe 15 and a gasoline and lighter portion passing overhead through pipe 16. This gasoline and lighter portion enters fractionator 17 and is there separated into a raw gasoline fraction leaving through pipe 18 and a gas fraction high in olefinic content leaving through pipe 19. In the preferred form of operation, this gaseous fraction passing through pipes 19 and 20 may be 35 compressed by compressor 21 and then passes through pipe 22 and pipe 23 into heating coil 24 in furnace 6 where it is heated to a temperature appropriate for the following step and passes through pipe 25 into a catalytic reactor 26. In this catalytic reactor 26 the olefine containing

gases are contacted under reaction conditions of temperature and pressure with a solid particle form adsorbent contact mass to bring about their polymerization into materials largely of gasoline boiling range. Effluent vapors from reactor 26 pass through pipe 27 and may, by means of valve 28 be introduced into fractionator 14 at the same point as are vapors from vapor separator 9 or, valve 29 being closed, they may be introduced through pipe 29 to a higher level in fractionator 14, there to be fractionated along with the vapors from the original gas oil cracking.

Frequently, and especially in the case where stocks of relatively high sulfur content are originally cracked, in the gas oil cracking step, it is desirable to reduce the sulfur content of the gaseous products prior to their treatment and especially to reduce the amount of hydrogen sulfide and similar readily reactive sulfur compounds which may be present. In this case, with valve 30 closed, the gases from pipe 20 will be passed through pipe 31 into a scrubber 32 wherein they may be scrubbed by caustic soda solution or other appropriate alkaline reagent introduced through pipe 33 and leaving through pipe 34. The scrubbed gases in this case will pass from scrubber 32 through pipe 35 and reenter pipe 20 through pipe 36, being disposed of afterward in the usual fashion. In many cases, particularly if a relatively long cut of these gases has been made, it will be desirable to divert these gases through valve 37 to pass through a partial condenser 38 and into receiver 39 wherein a liquid/vapor separation occurs, the vapor being passed through pipe 40 to compressor 21, and the liquids being passed by the agency of pump 41 into pipe 23 for treatment in the polymerization reaction.

It is also frequently desirable to utilize the condenser 38 and receiver 39 to effect a rough separation between gases to be treated and a liquid fraction which it is not desired to treat, in which case that liquid may be withdrawn from the system through pipe 42. In other cases, liquid from receiver 39 may be passed through pipe 43 to be included with the gasoline withdrawn from the bottom of fractionator 17 for stabilization and disposal in a manner hereinafter disclosed.

Fractionator 17 may also be so operated as to produce a gas cut, which overhead gas cut passes under system pressure through pipe 19 and pipe 44 and is introduced directly into pipe 23 to pass through the polymerizing step under that system pressure.

Fractionator 17 may also be so operated as to produce a bottoms cut which comprises the heavier portions of the desired gasoline, a side cut which comprises lighter portions of gasoline containing olefinic materials emergent from the fractionator through pipe 45 and a gas cut emergent from the fractionator overhead through pipe 19. In this case the overhead gas cut may be handled in any of the ways hereinbefore set forth and it will be usual to take the side cut produced through pipe 45 and pass it through pipes 46 and 47, valve 49 being closed, to condenser 38 and receiver 39, after which through the agency of equipment hereinbefore explained, both the side cut of light gasoline and the overhead cut of gases may be combined and passed through pipe 23, heating coil 24 and the polymerization reactor 26.

It will be noted that a pipe 50 is provided in order that liquid from pipe 23 may be utilized,

if desired, as wet reflux for control of the top temperature of fractionating tower 17. It will also be noted that a pump 51 and pipe 52 are provided so that liquid product from the bottom of fractionator 17 may be utilized as wet reflux for control of the temperature at the top of fractionator 14.

In case fractionator 17 is utilized to cut simply between a raw gasoline and an overhead vapor cut, the raw gasoline emergent from fractionator 17 through pipe 18 is diverted through pipe 53, valve 54 being closed, to enter stabilizer 55 wherein the gasoline is stabilized to a desired vapor pressure which may be, if desired, a relatively low vapor pressure for more complete removal of olefinic materials, to later be raised by addition of light materials from another source. Stabilized gasoline departing through pipe 56 is removed from the system as gasoline product at the lower extremity of pipe 18 in the flow sheet shown. Overhead stabilizer gases leaving the stabilizer through pipe 57 are cooled, condensed and collected in the customary setup of cooler 58, condenser 59 and receiver 60, thereafter to be forwarded by pump 61 through pipe 62 to pipe 23 to be treated in the polymerization reaction, a portion being diverted through pipe 63 for the control of the stabilizer.

Returning now to the polymerization reactor 26, we find this reactor to be supplied with a solid particle form catalytic material through pipe 64, hopper 65, and appropriate controlled feed leg 66. Spent contact masses from this reactor removed through controlled drain leg 67 is collected in a hopper 68. It is therein preferably reduced into a slurry through the agency of gas oil supplied by pipe 69 and passes from hopper 68 in slurry form through pipe 10 to be introduced into the gas oil cracking reaction.

Turning to the bottom of fractionator 14, the heavier than gasoline or recycle gas oil cut collected therein, is drawn upon by pump 70 and passed through pipe 71 from whence a portion or all may be diverted through pipe 72 to supply the quenching requirements of the operation through pipe 12 and/or the slurry producing requirements of the operation through pipe 69. Also material from pipe 71 may pass through pipe 13 to assist in introduction of the slurry into the gas oil cracking system as well as to serve as recycle therein. It will be noted that, if desired, all of the recycle stock produced in fractionator 14 may thus be recycled to the gas oil cracking operation. If it is not desired to recycle all of this material, a portion may be withdrawn from the system through pipe 74. It will also be noted that a light gas oil fraction may be withdrawn, if desired, from tower 14 through pipe 75.

The gas oil cracking operation may be conducted in vapor phase, in liquid phase or in mixed phase condition. The process also may be used to crack or vis-break heavier charge stocks. Most usually, the process will be conducted either in vapor phase or in a mixed phase condition bordering upon complete vaporization.

The gas oil cracking will ordinarily be conducted at temperatures in the range of from about 1000° F. to about 1100° F. and at pressures of the order of 400 to 500 p. s. i. gauge or more, in the presence of from about 2 pounds to about 10 pounds of contact mass per barrel of total charge to furnace. Such a process will produce, from normal gas oil upon a once through basis, from about 20% to about 50% of gasoline of 400° F. end point by volume on gas oil consumed in

process, together with from about five to about twenty percent of gases, (by weight on charge consumed), which gases are highly olefinic in nature and principally composed of C₃ and C₄ materials. Such gases, when treated in the polymerization step at temperatures of the order of 500° F. to 1000° F., preferably at about 700° F.-750° F. in the presence of an alumina-silica catalyst in amounts appropriate for the system, are converted largely into materials of gasoline boiling range. Thus the combined process is found capable of producing from about thirty to about sixty per cent of gasoline of high value from net gas oil consumed in process.

The polymerization operation is shown herein as an operation wherein the catalyst is employed as a downwardly moving bed of contact mass material. The operation at this stage is not restricted to such a process and may be conducted either in this manner or as one wherein the catalyst is suspended by the reactant vapors in a condition of hindered settling. It is also within the contemplation of this invention that a series of fixed bed catalyst chambers might be used alternately, the bed in each chamber being discharged to hopper 68 after use and the reactor chamber being re-filled.

The solid particle form adsorptive catalytic contact mass to be used both in the gas-oil cracking step and in the olefine polymerization step may be any one of a number of forms of metallic oxide catalyst. Most usually the catalyst will be of the nature of an alumina or alumina-silica complex, of natural or synthetic origin, such as fuller's earth, various other natural clay-like materials, including acid treated clays, and the like, various synthetic materials, such as those which may be prepared by the gelation of alumina and/or silica, either individually, with mixing, or with coprecipitation. Such alumina and/or silica complexes may also carry oxides of other metals, as chromia, vanadia, magnesia, manganese, etc., added as by mixture, impregnation, coprecipitation and the like. In normal operation, however, preference is had for the alumina/silica complexes either natural or synthetic, without added oxides of other metals, since these have the type of catalytic effect desired for the gas-oil cracking, and while they may be neither as selective nor as highly efficient as certain specialized catalytic materials for the olefine polymerization, this process permits their economic use in such proportions as actually to achieve an enhanced production against the use of such catalysts. In general, therefore, the process contemplates the use of any solid, adsorbent polymerization catalyst which is stable under the cracking conditions and hence can serve in both operations of the process.

The catalytic contact mass may be utilized either as relatively small particles, such as those used in contact filtration, in the form of granules such as the ordinary particles of fuller's earth used in percolation filtration, or in the form of prepared pellets, spheres and the like of relatively small size, such as many of the synthetically prepared catalysts.

Many variations of the invention herein set forth will occur to the man skilled in the art when installing and practising this invention. All such I consider as within the scope of my invention except as limited by the claims herein-after set forth.

I claim:

1. In a process for the conversion of hydro-

carbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive contact mass maintained in suspension in said charge, separating the products of such cracking into vapors

5 and a liquid fraction containing the suspended solid, fractionating the vapors into an olefine containing fraction, a gasoline, and a heavier-than-gasoline fraction, contacting the olefine fraction at reaction conditions of temperature and pressure with a solid particle form adsorptive catalytic contact mass to convert a substantial portion thereof to material of gasoline boiling range, passing the vaporous products of such conversion to common fractionation with the 10 vapors of the first cracking operation, removing contact mass from the olefine conversion stage, and injecting said contact mass into suspension in the hydrocarbon in the first cracking operation.

2. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive contact mass maintained in suspension in said charge, separating the products of such cracking into vapors 15 and a liquid fraction containing the suspended solid, fractionating the vapors into an olefine containing fraction, a gasoline, and a heavier-than-gasoline fraction, removing sulfur from the olefine fraction, contacting the olefine fraction with a solid-particle form adsorptive catalytic contact mass to convert a substantial portion thereof to material of gasoline boiling range, passing the vaporous products of such conversion to common fractionation with the vapors of the 20 first cracking operation, removing contact mass from the olefine conversion stage, and injecting said contact mass into suspension in the hydrocarbon in the first cracking operation.

3. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive contact mass maintained in suspension in said charge, separating the products of such cracking into vapors 25 and a liquid fraction containing the suspended solid, fractionating the vapors into an olefine containing fraction, a gasoline, and a heavier-than-gasoline fraction, removing sulfur from the olefine fraction, contacting the olefine fraction at reaction conditions of temperature and pressure with a solid-particle form adsorptive catalytic contact mass to convert a substantial portion thereof to material of gasoline boiling range, passing the vaporous products of such conversion to common fractionation with the vapors of the 30 first cracking operation, removing contact mass from the olefine conversion stage, and injecting said contact mass into suspension in the hydrocarbon in the first cracking operation.

4. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive contact mass maintained in suspension in said charge, separating the products of such cracking into vapors 35 and a liquid fraction containing the suspended solid, fractionating the vapors into an olefine containing fraction, a gasoline, and a heavier-than-gasoline fraction, removing sulfur from the olefine fraction, contacting the olefine fraction at reaction conditions of temperature and pressure with a solid-particle form adsorptive catalytic contact mass to convert a substantial portion thereof to material of gasoline boiling range, passing the vaporous products of such conversion to common fractionation with the vapors of the 40 first cracking operation, removing contact mass from the olefine conversion stage, and injecting said contact mass into suspension in the hydrocarbon in the first cracking operation.

5. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive contact mass maintained in suspension in said charge, separating the products of such cracking into vapors 45 and a liquid fraction containing the suspended solid, fractionating the vapors into an olefine containing fraction, a gasoline, and a heavier-than-gasoline fraction, removing sulfur from the olefine fraction, contacting the olefine fraction at reaction conditions of temperature and pressure with a solid-particle form adsorptive catalytic contact mass to convert a substantial portion thereof to material of gasoline boiling range, passing the vaporous products of such conversion to common fractionation with the vapors of the 50 first cracking operation, removing contact mass from the olefine conversion stage, and injecting said contact mass into suspension in the hydrocarbon in the first cracking operation.

6. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive contact mass maintained in suspension in said charge, separating the products of such cracking into vapors 55 and a liquid fraction containing the suspended solid, fractionating the vapors into an olefine containing fraction, a gasoline, and a heavier-than-gasoline fraction, removing sulfur from the olefine fraction, contacting the olefine fraction at reaction conditions of temperature and pressure with a solid-particle form adsorptive catalytic contact mass to convert a substantial portion thereof to material of gasoline boiling range, passing the vaporous products of such conversion to common fractionation with the vapors of the 60 first cracking operation, removing contact mass from the olefine conversion stage, and injecting said contact mass into suspension in the hydrocarbon in the first cracking operation.

7. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive contact mass maintained in suspension in said charge, separating the products of such cracking into vapors 65 and a liquid fraction containing the suspended solid, fractionating the vapors into an olefine containing fraction, a gasoline, and a heavier-than-gasoline fraction, removing sulfur from the olefine fraction, contacting the olefine fraction at reaction conditions of temperature and pressure with a solid-particle form adsorptive catalytic contact mass to convert a substantial portion thereof to material of gasoline boiling range, passing the vaporous products of such conversion to common fractionation with the vapors of the 70 first cracking operation, removing contact mass from the olefine conversion stage, admixing said contact mass with at least a portion of the heavier-than-gasoline fraction from said fractionation, and injecting said contact

mass into suspension in the hydrocarbon in the first cracking operation.

4. In a process for the conversion of hydrocarbons of higher boiling point to motor fuel of high quality the steps which comprise: subjecting a liquid hydrocarbon to cracking at temperatures between about 1000° F. and about 1100° F. to convert a substantial portion thereof to gasoline and other portions thereof to olefines, in the presence of a solid, particle-form adsorptive contact mass maintained in suspension in said charge, separating the products of such cracking into vapors and a liquid fraction containing the suspended solid, fractionating the vapors into an olefine containing fraction, a gasoline, and a heavier-than-gasoline fraction, contacting the olefine fraction at reaction conditions of temperature and pressure with a solid particle-form adsorptive catalytic contact mass to convert a substantial portion thereof to material of gasoline boiling range, passing the vaporous products of such conversion to common fractionation with the vapors of the first cracking operation, removing contact mass from the olefine conversion stage, and injecting said contact mass into suspension in the hydrocarbon in the first cracking operation.

5. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, in the presence of a solid, particle-form adsorptive alumina-silica contact mass maintained in suspension in said charge, separating the products of such cracking into vapors and a liquid fraction containing the suspended solid, fractionating the vapors into an olefine containing fraction, a gasoline, and a heavier-than-gasoline fraction, contacting the olefine fraction at reaction conditions of temperature and pressure with a solid particle-form adsorptive catalytic alumina-silica contact mass to convert a substantial portion thereof to material of gasoline boiling range, passing the vaporous products of such conversion to common fractionation with the vapors of the first cracking operation, removing contact mass from the olefine conversion stage, and injecting said contact mass into suspension in the hydrocarbon in the first cracking operation.

6. In a process for the conversion of hydrocarbons of higher boiling point to motor fuel of high quality the steps which comprise: subjecting a liquid hydrocarbon to cracking at temperatures between about 1000° F. and about 1100° F. to convert a substantial portion thereof to gasoline and other portions thereof to olefines, in the presence of a solid, particle-form adsorptive contact mass maintained in suspension in said charge, separating the products of such cracking into vapors and a liquid fraction containing the suspended solid, fractionating the vapors into an olefine containing fraction, a gasoline, and a heavier-than-gasoline fraction, contacting the olefine fraction at reaction conditions of temperature and pressure with a solid-particle-form ad-

sorptive catalytic contact mass to convert a substantial portion thereof to material of gasoline boiling range, passing the vaporous products of such conversion to common fractionation with the vapors of the first cracking operation, removing contact mass from the olefine conversion stage, admixing said contact mass with at least a portion of the heavier-than-gasoline fraction from said fractionation, and injecting said contact mass into suspension in the hydrocarbon in the first cracking operation.

7. In a process for the conversion of hydrocarbons of higher boiling point to motor fuel of high quality the steps which comprise: subjecting a liquid hydrocarbon to cracking conditions of time, temperature and pressure to convert a substantial portion thereof to gasoline and other portions thereof to olefines, said cracking being conducted at a pressure sufficient to cause retention of liquid state by at least a portion of said charge and in the presence of a solid, particle-form adsorptive contact mass maintained in suspension in said charge, separating the products of such cracking into vapors and a liquid fraction containing the suspended solid, fractionating the vapors into an olefine containing fraction, a gasoline, and a heavier-than-gasoline fraction, contacting the olefine fraction at reaction conditions of temperature and pressure with a solid, particle-form adsorptive catalytic contact mass to convert a substantial portion thereof to material of gasoline boiling range, passing the vaporous products of such conversion to common fractionation with the vapors of the first cracking operation, removing contact mass from the olefine conversion stage, and injecting said contact mass into suspension in the hydrocarbon in the first cracking operation.

8. In a process for the conversion of hydrocarbons of higher boiling point to motor fuel of high quality the steps which comprise: subjecting a liquid hydrocarbon to cracking at temperatures between about 1000° F. and about 1100° F. to convert a substantial portion thereof to gasoline and other portions thereof to olefines, said cracking being conducted at a pressure sufficient to cause retention of liquid state by at least a portion of said charge and in the presence of a solid, particle-form adsorptive contact mass maintained in suspension in said charge, separating the products of such cracking into vapors and a liquid fraction containing the suspended solid, fractionating the vapors into an olefine containing fraction, a gasoline, and a heavier-than-gasoline fraction, contacting the olefine fraction at reaction conditions of temperature and pressure with a solid-particle-form adsorptive catalytic contact mass to convert a substantial portion thereof to material of gasoline boiling range, passing the vaporous products of such conversion to common fractionation with the vapors of the first cracking operation, removing contact mass from the olefine conversion stage, admixing said contact mass with at least a portion of the heavier-than-gasoline fraction from said fractionation, and injecting said contact mass into suspension in the hydrocarbon in the first cracking operation.

ARTHUR V. DANNER.
